REFLECTOR FOR FISH TANKS

Julius C. Bruno, Newark, N. J., assignor to General Designs, Inc., a corporation of New Jersey

Application September 15, 1955, Serial No. 37,943

Term of patent 7 years

(Cl. D91—2)

FIG. 1.

FIG. 4.

FIG. 2.

FIG. 3.

Fig. 1 is a top perspective view of the reflector for fish tanks embodying my new design;

Fig. 2 is a top plan view thereof;

Fig. 3 is a front elevational view thereof; and

Fig. 4 is a vertical sectional view taken on the line 4—4 of Fig. 2 and looking in the direction of the arrows.

I claim:

The ornamental design for a reflector for fish tanks, as shown.
